ARTHUR GROHMAN, OF WILMINGTON, DELAWARE.

BOAT-LAUNCHING APPARATUS.

1,265,771.

Specification of Letters Patent. Patented May 14, 1918.

Application filed October 14, 1916. Serial No. 125,719.

To all whom it may concern:

Be it known that I, ARTHUR GROHMAN, a citizen of Germany, and a resident of Wilmington, in the county of New Castle and State of Delaware, have invented new and useful Improvements in Boat-Launching Apparatus, of which the following is a specification.

This invention relates to devices for launching boats from the deck of a ship.

The object of my invention is to provide means whereby all the boats alined on the deck of a ship may be quickly and safely launched simultaneously from both sides of the ship or from either side.

Another object of this invention is to provide a launching apparatus which is controlled from aboard and adapted to launch the life boats from the boat deck of the ship and lowered in steps, first alongside of one of the passenger decks then along another passenger deck and finally lowered to the side.

A further object of this invention is an apparatus adapted for launching boats from the deck of a ship and to securely hold the boats at such a distance from the ship to prevent them from being capsized or thrown against the sides of the ship.

With the above and related objects in view, this invention comprises the construction, combination and arrangement of parts hereinafter described, a practical embodiment whereof is illustrated in the accompanying drawing and is embraced within the scope of the appended claims.

In the said drawing, Figure 1 is a plan view of a portion of the boat deck of a ship showing my improved launching apparatus; Fig. 2 is a fragmentary sectional elevation of the ship; Fig. 3 is a fragmentary side elevation of an improved launching device; Fig. 4 is a fragmentary front elevation thereof; Fig. 5 is a view in the rear of that of Fig. 4; Fig. 6 is a side elevation of a portion of the ship; Fig. 7 is a view partly in section of the means for operating the launching apparatus; Fig. 8 is a view at right angles to that of Fig. 7 and Fig. 9 is an enlarged view of a section of the ship illustrating the step by step launching of a boat from the deck of the ship.

Referring more particularly to the drawing for a detail description of my invention, 10 represents the boat deck of a ship, 11

represents an upper passenger deck and 12 represents a lower passenger deck. 13 represents a davit whose shank is hinged to a bolt 14 mounted in a socket 15 fastened to the side of the ship to allow the davit to swing outwardly of the side of the ship; 16 represents a clamp spanning the shank of the davit and adapted to prevent the davit from swinging. 17 represents a pair of bolts to each clamp and provided with nuts adapted to tighten the clamp, one of which nuts may be loosened and the other removed from its bolt to permit the clamp to release the davit. Above the shank the davit is arched, as shown, the arched portion passing through a recess of the boat deck.

18 represents a guy having one end fastened to the boat deck and the opposite end connected by a tackle at the top of the davit. 19 represents a life boat on top of the boat deck suspended from a pair of davits by tackles 20. Each pair of davits is joined by a rope 20^a, which, together with an oppositely disposed pair of guys 18, prevent the relative displacement of the davits.

21 represents a pair of guides mounted on the boat deck and provided with cam grooves 22. 23 represents a rack link provided with teeth on its under surface and having its front end hinged with a davit and its rear end provided with a roller 24 supported to roll along the cam groove of the guides. 25^a and 25^b represent countershafts supported longitudinally of the ship in front of the guides 21 by bearings or brackets 26. 90 On each counter-shaft, between each pair of brackets, is mounted a spur gear 27 to mesh with the rack 23, the rack being held in mesh by a roller 28 supported to roll over the top of the rack by a bracket 29, said bracket being supported to swing on the shaft on opposite sides of the gear 27.

30 represents a pair of stanchions provided with bearings for a tubular shaft 31. 32 represents a shaft projected through the shaft 31, one end of the shaft 32 carrying a wheel 33 and the opposite end carrying a gear 34. The gear 34 is in mesh with a larger gear 35 carried by a stud provided with a smaller gear 36. 37 represents a larger gear 105 carried by the shaft 31 and is in mesh with the gear 36. The shaft 31 is provided with a pair of ratchet-wheels 38^a and 38^b. 39^a and 39^b represent a pair of clicks, the click 39^a being adapted to engage the ratchet 38^a 110

and the click 39^b being adapted to engage the ratchet 38^b in opposition to that of the ratchet 39^a.

The shaft 31 is provided with a worm in 5 mesh with a worm gear 40. The gear 40 is mounted on a stud carrying a pair of spur gears 41^a and 41^b. 42 represents a standard provided with a bearing for the adjacent ends of shafts 43^a and 43^b supported transversely of the ship by bearings or brackets 44. The opposite ends of the said shafts 43^a and 43^b are connected with the counter-shafts by beveled gears 45.

The gears 41^a and 41^b are respectively in 15 mesh with gears 46^a and 46^b. The gear 46^a is carried by a sleeve slidingly keyed on the shaft 43^a and the gear 46^b is similarly carried by a sleeve slidingly keyed on the shaft 43^b. A lever 48^a is adapted to move the gear 20 46^a into or out of mesh with the gear 41^a, and the lever 48^b is adapted to move the gear 46^b into or out of mesh with the gear 41^b.

From the above description, it will be 25 readily understood that the life boats, which are shown to be stowed on opposite sides of the boat deck may be launched, and if launched may be stowed either simultaneously from both sides of the ship or from either side. Thus to launch the boats from 30 both sides of the ship, the gears 46^a and 46^b are moved into mesh by their respective levers, and when the wheel 32 is turned in the direction of the arrow, the counter-shafts will turn in opposite directions to 35 actuate the launching apparatus to cause the davits carrying the boats to swing outwardly from the sides of the ship. By forcing either one of the said gears 46^a or 46^b out of mesh with its corresponding gear, one 40 of the counter-shafts will be disconnected and the turning of the wheel 32 will result in launching the boats from one side of the ship only. It will also be understood that when the wheel 32 is revolved in an oppo- 45 site direction to that shown by the arrow, the process is reversed, that is, the davits will be caused to swing inwardly of the side of the ship, and carrying the boats in position for stowing.

50 Assuming now that the wheel 32 is turned in a direction for launching the boats from one side of the ship only, the motion of the wheel is transmitted by way of the herein-before described gearing and transversely 55 disposed shaft to the counter-shaft which is thus caused to rotate with its gears in a direction to actuate the racks to move outwardly from the deck of the ship. It will be observed there is a pair of racks to each 60 pair of davits. Each pair of racks will, therefore, during the outward movement, force the davits to swing outwardly from the side of the ship and thus carry the boat suspended from said pair of davits away 65 from its cradle 50 and off the boat deck of

the ship. Assuming that the davits have been swung in the position shown in the first dotted lines in Fig. 9, the boat may then be lowered from the davits and the davits caused to swing in the opposite direction 70 to bring the boat alongside the first passenger deck of the ship. After the passengers of said first deck have boarded the boats, the boats are lowered until they are in line with the second passenger deck. The davits may 75 then be caused to swing outwardly of the ship until they are in a position shown in dotted lines in Fig. 2 while the boat may be launched as shown. When the boats are in the water they need not be detached from 80 the davits, as the davits will prevent the boats from being thrown by the sea against the sides of the ship, being held rigidly by the racks. Thus time may be given for any- 85 one who remained on board ship to reach the boats. Also each boat's crew may first get ready for operating the boat and wait for the first opportunity when it is safe to steer away from the ship and then disconnect the boat from the davits. 90

Having thus described my invention and the advantages to be derived therefrom, what I claim as new and desire to protect by Letters Patent is:

1. An apparatus for launching a life boat 95 from the deck of a ship comprising a pivotally supported davit, an actuating mechanism therefor comprising a member adapted to swing in the plane of the davit, and a cam engaging said member and controlling 100 and limiting the extent of said swing.

2. An apparatus for launching a life boat from the deck of a ship comprising a pivotally supported davit, an actuating rack link 105 therefor pivoted to and adapted to swing in the plane of the davit, and means for guiding the free end of the link to keep the rack at all times in mesh with a fixed driving pulley.

3. An apparatus for launching life boats 110 from the deck of the ship comprising a pair of davits to each boat, means supporting the davits to swing in a vertical plane, a rack pivotally connected with each davit, means for guiding the racks transversely 115 of the deck, said guiding means provided with cam slots adapted to cause the racks to swing in the plane of the davits.

4. An apparatus for launching two life boats from a deck on the opposite sides of 120 a ship, comprising a pair of davits to each boat, each pair of davits supported to swing in a vertical plane in the direction opposite to that of the other pair, a rack to each davit, means for guiding the racks of each 125 pair of davits transversely of the deck, said guiding means adapted to cause the racks to swing in the plane of the davits.

5. An apparatus for launching a life boat from the deck of a ship, a pair of davits to 130

each boat supported to swing in a vertical plane, a rack to each davit, a cam adapted to guide the rack transversely of the deck and to cause it to swing in the plane of the davits, and means on board ship to control the movement of the racks.

6. An apparatus for launching life boats from the deck of a ship, comprising a pair of davits to each boat supported to swing in a vertical plane, a rack link with each davit, means for guiding the rack transversely of the deck, a driving shaft, a gear mounted thereon to mesh with the rack, and a roller bearing for the rack supported to swing in the plane of the davits.

7. An apparatus for launching a life boat from the deck of a ship comprising pivot-

ally supported davits, an actuating rack link pivoted to each davit and extending cross-wise of the ship, a driving pinion for said rack link, and a swinging yoke mounted on the same center as the pinion and embracing the rack link acting to hold it at all times in mesh with the pinion, together with camways for guiding and limiting the throw of the rack links.

In testimony whereof, I have signed this specification in the presence of two subscribing witnesses.

ARTHUR GROHMAN.
